UNITED STATES PATENT OFFICE.

JOSEPH WOLFF, OF BROOKLYN, NEW YORK, ASSIGNOR, BY MESNE ASSIGNMENTS, TO SONORA PHONOGRAPH COMPANY, INC., A CORPORATION OF NEW YORK.

NEEDLE REST.

Application filed May 5, 1919. Serial No. 294,800.

My invention relates to devices upon which the needle or stylus and the sound-box or reproducer of a talking machine is adapted to rest when in inoperative position.

The object of the invention is to provide a device for supporting the reproducer and its stylus when in inoperative position, whereby the stylus will not be injured, which will not itself be injured by the stylus, and which will not detract from the appearance of the talking machine.

A further object of the invention is to provide a structure, of the character herein described, which is extremely simple in construction, reliable and efficient in its purpose, and inexpensive to manufacture.

These and further objects will more fully appear in the following specification and accompanying drawings considered together or separately.

I have illustrated one embodiment of my invention in the accompanying drawings in which like parts in all of the figures are designated by similar reference characters, and in which,—

Fig. 1 is a plan view of a portion of a talking machine embodying my invention;

Fig. 2 is a side elevation of the same part 30 in section; and

Fig. 3 is a detail view of a modification.

In the drawings 1 designates the motor board of a talking machine cabinet, below which is the usual motor and amplifier (not 35 illustrated).

A tone-arm 2 is carried on the motor board and is adapted to rotate in the plane of the board. The tone-arm carries a pivoted tubular extension 3, to the outer extremity of which is secured a sound-box 4. The sound-box 4 is provided with the usual diaphragm, to the center of which is secured a stylus arm 5 pivoted at 6 to the sound-box. The outer extremity of the stylus arm 45 carries a socket 7 in which a stylus 8 is secured by means of a set screw 9.

Carried on the motor board 1 is a pad or rest 10. The pad is positioned outside of the periphery of the turn-table 11 whereby 50 when the sound-box is resting on the pad, as shown, the surface of the turn-table will be cleared.

The pad is a brush-like structure, preferably of soft rubber, and comprises a foun-

dation 12 and a plurality of projections 13. 55 The pad may be of any desired shape or configuration, and may be carried in the casing 14, as shown. The casing may be secured to the motor board in any desired manner. It will be understood that if desired the casing may be omitted and the pad be directly secured to the board.

In Fig. 3, I have shown a modification illustrating a pad comprising a brush consisting of a back 15 and bristles 16. The brush may or may not be carried in a casing. If a casing is employed it may be like that shown in Fig. 2, or the walls 12 may extend upward to the level of the ends of the bristles as shown.

When the sound-box is positioned on the rest, the extremity of the stylus arm and the set screw will engage the ends of the members 13 or 16, as the case may be, and the point of the needle will rest between the members and be protected from harm.

The pad shown in Figs. 1 and 2, being of soft rubber, the point of the needle will not be injured even should it come in contact with the foundation 12.

A needle rest pad constructed of soft rubber as herein described is more durable than one made of felt, velvet, or other similar material, as in the latter type of pad the indentation made by the needle causes the material to wear rapidly, and thus detract from the appearance of the instrument.

In accordance with the provisions of the patent statutes, I have described the principle of my invention together with the apparatus which I now consider to represent the best embodiment thereof, but I desire to have it understood that the apparatus shown is merely illustrative, and that the invention can be carried out in other ways without departing from the spirit of my invention.

Having now described my invention, what I claim and desire to secure by Letters Patent is:—

1. In a phonograph reproducer support, 100 a stylus bar, a stylus carried by said stylus bar, said stylus projecting beyond and being of less diameter than said stylus bar, a rest to support said stylus bar and stylus when in inoperative position, said rest comprising a pad having an elastic surface, and a plurality of erect, elastic columnar members projecting above said surface a distance

slightly greater than the distance from the end of said stylus bar to the point of said stylus, said members being spaced apart a distance greater than the diameter of the stylus and less than the diameter of the stylus bar, to permit said stylus to pass freely between said members but to cause the tops of a plurality of said members to engage said stylus bar, whereby the weight of the stylus bar is borne by said members while the stylus projects below the tops of and is surrounded by said columnar members.

2. In a phonograph reproducer support, 15 a stylus bar, a stylus carried by said stylus bar, said stylus projecting beyond and being of less diameter than said stylus bar, a rest to support said stylus bar and stylus when in inoperative position, said rest comprising

ing a pad of soft rubber having a plurality 20 of integral erect columns projecting above the body of said pad, said columns being of a length slightly greater than the vertical distance from the end of the stylus bar to the point of the stylus, said columns being spaced apart a distance greater than the diameter of the stylus and less than the diameter of the stylus bar, whereby when the stylus bar and stylus are placed upon said pad, the stylus bar will be engaged and supported by the tops of a plurality of said columns, while the stylus will pass below the tops of said columns and be caged by said columns and the body of said pad.

This specification signed and witnessed 35 this 18th day of April, 1919.

JOSEPH WOLFF.
